UNITED STATES PATENT OFFICE.

SOLOMON KAUFMAN, OF NEW YORK, N. Y.

COLLAR BUTTON.

Application filed September 4, 1926. Serial No. 133,636.

My invention relates to a new and improved form of collar button.

One of the objects of my invention relates to a collar button having a non-circular head 5 which can be turned about a central axis, and which can be locked in a plurality of positions so as to enable the collar button to be readily inserted through the button holes of the collar or the like, and to enable 10 the said head to be moved to a locking position.

Another object of this invention is to provide a collar button of this type which shall be of simple and durable construction and 15 shall have a minimum number of parts.

Other objects of this invention will be set forth in the following description and drawings which illustrate a preferred embodiment thereof, it being understood that 20 the above general statement of the objects of my invention is intended to generally explain the same, and not to limit it in any manner.

Fig. 1 is a side elevation of my improved 25 collar button.

Fig. 2 is a section on the line 2—2 of Fig. 3.

Fig. 3 is an end view of Fig. 1, the collar button being shown in what may be termed 30 the "entering" position.

Fig. 4 is a section on the line 4—4 of Fig. 2.

Fig. 5 is a view similar to Fig. 3, the 35 head of the collar button being shown as having been turned 90°, so that the said head is in the "locking" position.

The collar button comprises a body portion 10, having a curved inner end so as to fit the contour of the neck of the user. The 40 body portion 10 is provided with a bore 15, said bore having a relatively wide portion adjacent the inner end of the body 10, and having a relatively narrow portion adjacent the outer end of the body 10. The head 45 11 of the collar button is provided with a narrow shank 18 which fits within the narrow portion of the bore 15. The inner end of the shank 18 is provided with a head 17, which fits within the wide portion of the 50 bore 15. A compression spring 16 tends

to force the head 17 inwardly, so as to force the inner side of the head 11 against the outer side of the body portion 10. The head 7 can be connected to the shank 18 in any suitable manner so as to enable the parts 55 to be assembled.

The inner face of the head 11 is provided with an angular projection 14 and the outer face of the body 10 is provided with a longitudinal angular groove 12. The walls of 60 the angular groove 12 are provided with transverse angular notches 13.

Hence, when the head of the collar button is in the position shown in Figs. 1 and 3, for example, the compression spring 16 causes 65 the head to be yieldingly held in the position shown. In this position the elongated head 11 can be readily inserted through the button holes of a shirt, collar, or the like.

After the collar button has been inserted 70 into the proper position, the head 11 can be readily pulled outwardly a short distance, so that it can be then turned around to have the angular projection 14 engage the transverse notches or depressions 13 in the walls 75 of the groove 12.

The head 11 is held in this locking position by means of the compression spring 16.

My improved collar button requires only two parts, both of which are strong and 80 substantial and it is free from locking pins or other small parts which can be injured by the manipulation of the collar button.

I have shown a preferred embodiment of 85 my invention, but it is clear that numerous changes and omissions can be made without departing from its spirit.

I claim:

A collar button having a rounded base fitting the curvature of the neck, an elliptical shank joined thereto, the top of said shank being bevelled to receive a button substantially ellipsoidal in shape resting upon said shank, a series of indentations in said shank adapted to receive said button in a 95 plurality of fixed positions and a spring connecting said shank and said button.

In testimony whereof I affix my signature.

SOLOMON KAUFMAN.
